CARTRIDGE RADIO TUNER

David Krechman, 329 S. McCarty Drive,
Beverly Hills, Calif. 90212

Filed Sept. 3, 1968, Ser. No. 13,376

Term of patent 14 years

Int. Cl. D14—03

U.S. Cl. D56—4

FIGURE 1 is a left side, top and front perspective view of a cartridge radio tuner, showing my new design;

FIGURE 2 is a rear, bottom and right side perspective view;

FIGURE 3 is a front elevational view;

FIGURE 4 is a rear elevational view; and

FIGURE 5 is a right side elevational view thereof.

I claim:

The ornamental design for a cartridge radio tuner, substantially as shown.
